2,551,847

HERMETICALLY SEALED OPERATING DEVICE

Filed April 5, 1947

Fig. 1

UNITED STATES PATENT OFFICE

2,551,847

HERMETICALLY SEALED OPERATING DEVICE

Rolland D. Nelson, Hales Corners, Wis., assignor
to McGraw Electric Company, a corporation of
Delaware

Application April 5, 1947, Serial No. 739,597

1 Claim. (Cl. 286—29)

1

This invention relates to an hermetically sealed operating device.

Hermetically sealed transformers are coming into more common use in the electrical industry and it is desirable to have metal to metal seals at all entrances to the transformer tank. Various seals for non-moving parts, such as bushing seals have been developed, and the covers of the tanks have been welded in place to provide an hermetically sealed transformer.

Objects of this invention are to provide a metal to metal seal for an operating device having a movable external operating part located on the outside of the tank and a movable internal part located on the inside of the tank or container and arranged to be operated by the externally located operating member and still maintain the hermetic metal to metal seal for the tank or container. A specific instance of the use of such a device is for tap changing for an hermetically sealed transformer though the device is capable of other uses such as resetting or tripping or operating hermetically sealed switches or other hermetically sealed apparatus.

An embodiment of the invention is shown in the accompanying drawings, in which:

Figure 1 is a plan view of the device.

Figure 2 is a vertical sectional view.

Referring to the drawing, it will be seen that a transformer tank or housing has been indicated by the reference character 1 and a flange member by the reference character 2. The flange 2 is brazed, welded, or otherwise secured to the tank and is provided with an internally threaded aperture into which a bearing bushing 3 is screwed. This bushing constitutes a bearing for the shaft 4 which is the operating shaft for a tap changer, a switch or other device shown in block form and indicated by the reference character 5. This device 5 whether it be a tap changer, a switch of some other type, or any other form of mechanism is the internally located member in an hermetically sealed casing or container such as the transformer tank 1.

An external operating member, such as the handle 6 is provided for operating the internally located member. The shaft 4 is provided with a laterally bent or offset portion 7 which is provided with a recess 8 at its upper end. A pin 9 is located within the recess 8 and the shaft 4, 7 is free to rotate without rotating the pin 9. The pin 9 is preferably integral with a metal disk 10 which has an outwardly projecting pin 11.

A flexible metal bellows 12 is soldered or otherwise secured in an air-tight manner to the disk

10 and flange 2 at its upper and lower ends, respectively. This bellows does not rotate but tilts from one position to another as the shaft 4, 7 is rotated.

5 Means, in the form of a slotted disk or crank member 13 is provided with a radial slot 14 which loosely receives the pin 11 and which moves the pin around when the disk is rotated thus causing rotation of the shaft 4, 7 without rotating either 10 the disk 10 or the bellows 12. If desired, a part of the lower face of the disk 13 may be slanting as indicated at 15 and located immediately above the disk 10. This will act to limit outward motion of the disk 10. A shaft 16 is formed integral with the disk 13 and is secured as by means of a pin 17 or in any other way to the external operating member 6.

A casing or housing 18 is attached to the flange 2 of the tank and protects the bellows 12 from 20 the weather and also furnishes a bearing for the shaft 16. If desired, a graduated plate 19 may be secured to the top of the housing 18 to indicate in conjunction with the operating member 6, the particular tap or position of the 25 internal member.

It will be noted that the member consisting of the disk 10 with its projecting pins 9 and 11 constitutes a coupling member between the external operating means and the shaft 4, 7, and 30 is pivotally or revolvably joined to the shaft 4, 7.

It will be seen that a novel form of metal to 35 metal hermetic seal has been provided whereby an internal member or mechanism located in an hermetically sealed container can be operated by an externally located operating member.

Although this invention has been described in 40 considerable detail, it is to be understood that such description is intended as illustrative rather than limiting, as the invention may be variously embodied and is to be interpreted as claimed.

I claim:

An hermetically sealed operating device comprising a container, an internally located device, a shaft for operating said internally located 45 device, said shaft projecting through said container and having a laterally deflected outer end at an angle to the axis of said shaft, a coupling member consisting of a disk having an outwardly projecting pin and an inwardly projecting pin, 50 said inwardly projecting pin being pivotally connected with the laterally deflected outer end of said shaft, a flexible metal bellows hermetically sealed to said disk and to said container and surrounding the laterally deflected end of said 55 shaft, a rotary external member operatively

coupled to said outwardly projecting pin, and a housing supported from said container and enclosing said bellows and furnishing a support for said rotary external member, said rotary member having a slanting inner face arranged to coact with said disk to limit outward motion of said bellows.

ROLLAND D. NELSON.
